UNITED STATES PATENT OFFICE.

ARTHUR W. MOEHLENBROCK, OF DES MOINES, IOWA.

HUMIDIFIER FOR FURNACES.

Application filed May 9, 1924. Serial No. 712,098.

To all whom it may concern:

Be it known that I, ARTHUR W. MOEHLENBROCK, a citizen of the United States, and a resident of Des Moines, in the county of Polk and State of Iowa, have invented a certain new and useful Humidifier for Furnaces, of which the following is a specification.

The object of my invention is to provide a humidifier for furnaces of simple, durable and inexpensive construction, which may be easily and quickly placed in operative position relative to the furnace, and which, when so placed, is capable of supplying moisture to the air within the furnace in proportion to the amount of heat carried by the air.

A further object is to provide a humidifier which may be easily and quickly placed in position on a furnace and which is capable of operating automatically, and at the same time being positive in its action.

A further object is to provide a humidifier so constructed and arranged that its various members may be easily and quickly assembled or taken apart for the purpose of cleaning or repairing.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a side elevation of my improved humidifier showing the manner in which it is mounted in a furnace, said furnace being illustrated in segmental section.

Figure 2 is an enlarged central and vertical view of the same taken on the line 2—2 of Figure 1, the supply tank for the same also being illustrated in elevation.

The numeral 10 indicates a furnace which is of the hot air type, and which is provided with the usual jacket 11. The said jacket 11 has a hood 12 in which the furnace pipes 13 are mounted. One side of the hood 12 is provided with a door opening 14 for the purpose of permitting my improved humidifier to be placed in position on the furnace 10 through the said opening. The door opening 14 is provided with a door 15 detachably connected therewith, for the purpose of closing the said door opening after the humidifier has been placed in position.

My improved humidifier comprises a body

portion 16 having a bottom 17 and an upright and circular wall member 18. The upper edge of the wall member 18 is provided with a conical shaped top member 19 which terminates in a vertically extending neck 20, and which has its outer surface screw threaded. The neck 20 is provided with a pipe union 21 for the purpose of operatively connecting the said neck with a vertically arranged discharge pipe 22. The said discharge pipe is provided with a collar 23 designed to support a cup 24. The said cup 24 has a circular side wall 25, the upper edge of which is provided with an outwardly and upwardly extending flange 26. The central portion of the bottom of the cup 25 is provided with an opening designed to receive the discharge pipe 22, said opening being provided with a sleeve 27 of a height equal to the height of the flange 26. By this arrangement it will be seen that an annular passage 28 is provided in the cup for receiving the water hereinafter mentioned.

The bottom member of the cup 25 is provided with a downwardly and outwardly extending nipple 29 to which a pipe 30 is secured by means of a pipe union 31. The lower end of said pipe 30 is connected to a nipple 32 located in the upright wall member 18 of the body portion 16, near the bottom edge of said upright member. Placed on the flange 26 is a conical shaped screen 33 having its apex end designed to be mounted in said flange 26. The upper end of the screen 33 is designed to receive a second conical shaped screen 34 having its apex end extending upwardly and surrounding the upper end of the discharge pipe 22.

The upper end of the discharge pipe 22 is provided with a deflector plate 35, which is of spherical shape and mounted in position above the upper end of said discharge pipe by means of spiders 36, said spiders having their inner ends connected to a sleeve 37 which is simply slipped over the upper end of the pipe with the said sleeve extending down through an opening in the upper end of the conical screen 34. The base of the screen 34 is slightly smaller in diameter than the base of the screen 33, as clearly shown in Figure 2.

A second nipple 38 is mounted in the upright wall member 18 to which is connected a horizontally arranged pipe 39 by means of the union 40. The pipe 39 has its free end extending outwardly through the casing 11

and connected with an elbow 41. The said elbow 41 is provided with an upwardly extending pipe 42 which is secured to the bottom of a supply tank 43 connected to one side of the furnace casing 11 by means of a bracket 44. The tank 43 is so arranged that its top edge will lie in a plane below the bottom of the cup 25 with the bottom of said tank above the bottom of the body portion 16.

The tank 43 is provided with a sight gauge 45 for the purpose of indicating the amount of water within the tank, said gauge being of the usual construction. A supply pipe 46 is provided for the tank 43 which has a control valve 47.

The operation of my improved humidifier is as follows:

Assuming that the tank 43 has been filled with water, and that the body portion 16 of the humidifier has been placed on top of the furnace 10, as clearly illustrated in the drawings, then it will be seen that the body portion 16 will also become filled with water, which will also fill the discharge pipe 22 to a point substantially even with the bottom of the cup 25 through the supply pipe 39. The pipe 30 will also be substantially filled with water. If no heat is applied to the furnace 10 it will be seen that practically no evaporation of the water within the body 16 will take place, but if a fire is built in the furnace 10 and the temperature considerably increased, a certain amount of steam and moisture will be given off from the water within the body portion 16, which will pass upwardly through the discharge pipe 22 and escape from beneath the deflector plate 35, and form a vapor which will mix with the air within the hood 12, thereby permitting a comparatively small amount of moisture to be mixed with the air. But if the temperature within the furnace is greatly increased, then the water within the body portion 16 will reach the boiling point, at which time the bubbles of steam will travel upwardly through the discharge pipe 22 and carry with them a portion of the water from the water chamber beneath, which will be discharged against the deflector plate 35, from where it will drip onto the outer surface of the conical screen 34 and a large portion of it will be taken up by the air in the form of vapor. The water will trickle down over the screen 34 and then engage the inner surface of the screen 33 where further evaporation will take place. Any water which succeeds in traveling to the lower end of the screen 33 will be discharged into the cup 25 from where it will drain through the pipe 30 to the water chamber of the body portion 16.

In this connection, it should be noted that the discharge pipe 22 should be about one-eighth to one-fourth of an inch inside diam-

eter, as the best operation of the device depends on the diameter of the pipe being such that steam generated from the body portion 16 will ascend readily through the discharge pipe at a temperature below the boiling point, and yet should be small enough so that when the water reaches the boiling point, the bubbles formed by the escape of steam will entirely fill the pipe, the said bubbles then acting as small pistons or plungers which simply elevate the water and discharge it violently against the deflector plate 35. Thus it will be seen that when the furnace is heated at a high temperature, not only the steam generated by the water within the body portion will be discharged through the pipe 25, but also a large amount of hot water which trickles down over the screens. This provides an additional amount of moisture when the furnace is heated at a temperature where a large amount of moisture is necessary.

Thus it will be seen that I have provided a humidifier which is capable of delivering moisture to the air in predetermined quantities and in proportion to the temperature of the air within the furnace. The pipe 39 is provided with an outer casing 48 which is for the purpose of partially shielding the said pipe from the intense heat from the furnace, as it is desirable to keep the water within the pipe 35 at as low a temperature as possible. If the water within the pipes 39 and 42 should become heated, then the steam bubbles would pass out through the tank 43 instead of the pipe 22, it being necessary for the device to operate to keep the water within the pipes 39 and 42 heavier than the water within the discharge pipe 22.

I claim as my invention:

1. A humidifier for hot air furnaces comprising a base member having a boiling chamber, a vertically arranged discharge pipe communicating with the upper end of said boiling chamber, a supply pipe communicating with the lower end of said boiling chamber, a deflector plate at the upper end of said discharge pipe, means for collecting the water from said deflector plate and distributing it so it will be readily taken up by surrounding air, and means for collecting any excess water and returning it to the said boiling chamber.

2. A humidifier for hot air furnaces comprising a body portion having a boiling chamber designed to be placed on top of a furnace, a supply tank, a pipe for conveying water from said supply tank to the boiling chamber at a point in the bottom of said chamber, a vertically arranged discharge pipe communicating with the top of said chamber, a deflector plate at the outer end of said discharge pipe, a conical shaped screen beneath said deflector plate, a second conical shaped screen arranged in a

- vertical position beneath the first said screen, the first said screen having its apex end upward and the second said screen having its apex end downward, a collector cup 5 for receiving the lower end of the last said screen, said cup being located in a plane above the said supply tank, and means for conveying water from said collector cup to the bottom of said boiling chamber.
- 10 3. A humidifier for hot air furnaces comprising a hollow cylindrical body portion having its lower end closed, a conical shaped cover for said body portion terminating in a vertically arranged discharge pipe, a cup member detachably secured to the said discharge pipe having an annular receiving passage and an upwardly and outwardly extending flange, an inverted conical shaped screen mounted in said flange, a second conical shaped screen mounted in 15 the upper end of the first said screen, the second screen having its apex end extending upwardly to receive the discharge end of said pipe, a spherical shaped deflector plate above said discharge pipe, a pipe for 20 conveying water from the annular passage of said cup to the lower side of said cylindrical body portion, a supply pipe also communicating with the lower portion of said cylindrical body portion, a supply tank 25 communicating with said supply pipe, a sight gauge for said supply tank, a supply pipe for said supply tank, and a controlling valve for the last said supply pipe, all 30 of the said pipes being detachably connected with the said body portion while the remaining members of said device are detachably connected with each other and their supporting members.
- 35 4. A humidifier for hot air furnaces comprising a hollow cylindrical body portion having its lower end closed, a conical shaped cover for said body portion terminating in a vertically arranged discharge pipe, a
- cup member detachably secured to the said discharge pipe having an annular receiving passage and an upwardly and outwardly extending flange, an inverted conical shaped screen mounted in said flange, a second conical shaped screen mounted in 40 the upper end of the first said screen, the second screen having its apex end extending upwardly to receive the discharge end of said pipe, a spherical shaped deflector plate above said discharge pipe, a pipe for 45 conveying water from the annular passage of said cup to the lower side of said cylindrical body portion, a supply pipe also communicating with the lower portion of said cylindrical body portion, a supply tank 50 communicating with said supply pipe, a sight gauge for said supply tank, a supply pipe for said supply tank, and a controlling valve for the last said supply pipe, all 55 of the said pipes being detachably connected with the said body portion while the remaining members of said device are detachably connected with each other and their supporting members.
- 60 5. A humidifier for hot air furnaces comprising a base member having a boiling chamber, a vertically arranged discharge pipe communicating with the upper end of said boiling chamber, a supply pipe communicating with the lower end of said boiling chamber, a deflector plate at the upper end of said discharge pipe, and means for collecting the water from said deflector plate and distributing it so it will be 65 readily taken up by surrounding air.
- 70 Des Moines, Iowa, April 24, 1924.
